UNITED STATES PATENT OFFICE.

JOHN C. VOSS, OF EL PASO, TEXAS.

OVEN-THERMOMETER.

SPECIFICATION forming part of Letters Patent No. 403,710, dated May 21, 1889.

Application filed October 26, 1888. Serial No. 289,172. (No model.)

To all whom it may concern:

Be it known that I, JOHN C. VOSS, of El Paso, in the county of El Paso and State of Texas, have invented a new and Improved 5 Oven-Indicator, of which the following is a specification, reference being had to the annexed drawings, forming a part thereof, in which—

Figure 1 is a front elevation of my improved 10 oven-indicator. Fig. 2 is a rear sectional elevation taken on line $w-w$ in Fig. 3. Fig. 3 is a plan view. Fig. 4 is a vertical transverse section taken on line $x-x$ in Fig. 1. Fig. 5 is a horizontal section taken on line $y-y$ in Fig. 1. Fig. 6 is a rear elevation of a modified 15 form of my improved apparatus; and Fig. 7 is a horizontal section taken on line $z-z$ in Fig. 6.

Similar letters of reference indicate corresponding parts in all the views.

The object of my invention is to provide an instrument for indicating the temperature of an oven, so that the fire may be regulated to secure the required temperature for any 25 particular article.

My invention consists in the construction and combination of parts, as will be herein-after described and claimed.

In the frame A is journaled the spindle B, 30 which projects beyond the face of the frame and carries the index C. The spindle B is provided with a weighted arm, D, which is adapted to throw the index C back to zero. To a stud, a, projecting from the front plate, 35 b, of the frame A, is secured a curved compound bar, E, formed of strips of brass and steel fastened together in any suitable way, but preferably by brazing. The free end of the compound bar E touches the weighted lever D, and is adapted to move forward the 40 said lever and index connected therewith through the spindle B whenever the curvature of the compound bar is changed by heat, the weighted lever being adapted to return 45 the index to zero when the pressure of the compound bar is removed.

The frame A is provided with studs c, which are inserted in the door F of the oven to which the indicator is applied, and support 50 the said frame, so that there is a space for

the circulation of the hot air of the oven between the plate b and the inner surface of the oven-door F. The spindle B extends through an opening in the door F, and upon the outer surface of the door is secured a curved scale, 55 G, in front of which the index C moves. A sector-shaped guard, H, secured to the door F covers and protects the greater portion of the index C. Upon the face of the guard H are the names of different articles of food, and 60 opposite the names there are figures representing the degrees of heat required for baking or roasting such articles. The fire by which the oven is heated is regulated to bring the index C to the figure on the scale indicating the temperature required for the particular article to be roasted or baked.

In the modification shown in Figs. 6 and 7 the spindle B' is provided with a spur-wheel, d, which meshes into the wheel e upon the 70 spindle B², the spindle B² carrying the index C, as in the other case. In all other respects the construction of the indicator is the same as that shown in Figs. 1 to 5, inclusive.

The gearing serves to multiply the motion 75 of the spindle B', thus rendering the instrument more delicate in its operation than when without gearing.

Having thus described my invention, I claim as new and desire to secure by Letters Patent— 80

1. In an oven-indicator, the combination, with a spindle having a lever and an index or pointer, of a compound bar secured at one end and bearing at its free end against one side of said lever, and a weight for returning 85 the lever to its normal position.

2. In an oven-indicator, the combination, with the spindle B, provided with the weighted lever D and the index C, carried by the spindle, of the curved compound bar E, arranged 90 to contact with the weighted lever D, substantially as specified.

3. In an oven-indicator, the combination, with the spindle B, provided with the weighted lever D and the index C, carried by the said 95 spindle, of the curved compound bar E, arranged to contact with the weighted lever D, and the scale G, substantially as specified.

4. In an oven-indicator, the combination, with the spindle B, provided with the weighted 100

lever D and the index C, carried by the said spindle, of the curved compound bar E, arranged to contact with the weighted lever D, and the scale G and guard H, having marked thereon different articles of food, together with figures indicating the temperature to which such articles should be subjected in the operation of roasting or baking, substantially as specified.

10 5. The combination, with the oven-door F, of the frame A, provided with studs c, the

spindle B, extending through the oven-door, the weighted lever D and index C attached to the said spindle, the compound bar E, arranged to act upon the weighted lever D, and the scale G, attached to the oven-door, substantially as specified.

JOHN C. VOSS.
